*Primary Examiner—Mitchell Siegel
Attorney, Agent, or Firm—Joseph H. Lee*[57] CLAIM

The ornamental design for a scoreline pattern for a golf club head, as shown and described.

DESCRIPTION

The sole FIGURE is a perspective view of the scoreline pattern for golf club head, the broken line showing of a wood-type golf club head is for illustrative purposes only and forms no part of the claimed design.

The broken lines which define the bounds of the claimed design form no part thereof.
